UNITED STATES PATENT OFFICE.

CARL A. HADLAND, OF OSTRANDER, MINNESOTA.

BUILDING-BLOCK.

1,377,149.

Specification of Letters Patent.

Patented May 3, 1921.

Application filed August 16, 1919. Serial No. 317,939.

To all whom it may concern:

Be it known that I, CARL A. HADLAND, a citizen of the United States, residing at Ostrander, in the State of Minnesota, have 5 invented new and useful Improvements in Building-Blocks, of which the following is a specification.

This invention relates to building blocks, particularly to those constructed of concrete, and has for its object the provision of 10 a reinforced concrete building block which is so constructed as to be substantially water proof.

An important object is the provision of a 15 building block of this character within which are formed holes which, when a plurality of blocks are assembled will provide a continuous air space throughout the wall.

Another object is the provision of a building block of this character in which are 20 embedded preferably galvanized sheet iron reinforcing plates which are connected by other reinforcing plates or by reinforcing wires, as preferred.

25 An additional object is the provision of a block of this character which will be simple and inexpensive in manufacture, highly efficient and durable in use, and a general improvement in the art.

30 With the above and other objects and advantages in view, the invention consists in the details of construction to be hereinafter more fully described and claimed, and illustrated in the accompanying drawing, in 35 which—

Figure 1 is a plan view of a block constructed in accordance with my invention,

Fig. 2 is a vertical longitudinal sectional view,

40 Fig. 3 is a horizontal longitudinal sectional view,

Fig. 4 is a view similar to Fig. 3, showing a slight modification,

45 Fig. 5 is a view similar to Fig. 3, showing still another modification, and

Fig. 6 is a detail view of one of the reinforcing plates.

Referring more particularly to the drawing, the numeral 10 designates my block as 50 a whole, which may be formed in a suitably constructed mold and which is rectangular in general outline though the ends are preferably concave, as shown at 11. Formed through the block are centrally extending 55 cylindrical holes 12 which not only reduce the weight of the block but which provide

an air space within a wall constructed from the blocks. Extending transversely across the major portion of the block are metallic reinforcing plates 13 which may be of any 60 suitable size and shape but which preferably extend substantially or entirely to the top and bottom surfaces of the block. As shown in Figs. 1, 2 and 3, these plates are plain and are formed simply from flat sheets of metal, 65 whereas in Fig. 4 these plates are shown as provided at their ends with laterally directed flanges 14 which add to the stiffness of the plates. In Fig. 5, these plates are shown as formed of corrugated metal, the 70 corrugations 15 adding greatly to the strength of the plate. In each instance the plates are provided with holes 15^a of any size, shape or arrangement.

Regardless of the particular formation of 75 the plates 13, the block is additionally reinforced by means of longitudinally extending reinforcing wires 16, two of which are employed on each side and these wires bear against the ends of the transverse plates 13 80 and have their terminals bent toward each other, as shown at 17.

In the formation of the block it is of course understood that the various reinforcing plates and wires are disposed at the 85 proper positions and held by any suitable means in such positions, after which the cement is poured into the mold and around the reinforcing members so that when the block is finished these various members will 90 be embedded therein and will be effectually concealed from view.

From the foregoing description and a study of the drawing, it will be apparent 95 that I have thus provided an extremely simple and inexpensive concrete block which will be very strong and rigid in its make-up, which will be consequently efficient and reliable in use, and which will be substantially moisture proof by virtue of the provision of 100 the various reinforcing plates extending across the major portion thereof.

While I have shown and described the preferred embodiment of my invention, it is of course to be understood that I reserve 105 the right to make such changes in the form, construction, and arrangement of parts as will not depart from the spirit of the invention or the scope of the subjoined claim.

Having thus described my invention, I 110 claim:—

A concrete building block having embed-

led therein a plurality of spaced, parallel vertically disposed transversely extending reinforcing plates extending across the major portion thereof and terminating flush with the upper and lower surfaces of the block, said reinforcing plates being each provided with a plurality of holes arranged in staggered rows, and a plurality of longi-

tudinally extending tie wires at each side of the block in engagement with the ends of said plates, said reinforcing wires extending beyond the outermost plates and having their ends inwardly directed.

In testimony whereof I affix my signature.

CARL A. HADLAND.
